HENRY HAROLD READ, OF LONDON, ENGLAND.

PACKING CASE.

Application filed July 27, 1921. Serial No. 487,855.

To all whom it may concern:

Be it known that I, HENRY HAROLD READ, of Cranbourne, 84, Cranley Gardens, Muswell Hill, London, N. 10, England, a British subject, have invented certain new and useful Improvements in or Relating to Packing Cases, of which the following is a specification.

This invention relates to packing cases of the kind which are bound with strips of iron disposed in grooves and has for its object to provide improved means for preventing pilfering during transit, of goods in the packing cases bound with strips of hoop iron.

According to this invention hoop iron binding strips are secured around a packing case in grooves in the body of said case, by means of rivets, nails, wire or the like, hereinafter called fasteners, the outer ends of said fasteners being sealed to said strips by soldering or the like.

Preferably the binding strips are secured to the sides and to the bottom of the packing case by nails or bifurcated rivets the heads of which lie inside said case and the outer ends of which are bent over the binding strip and sealed thereto with solder. When the lid of the case has been placed in position and secured by usual means, the ends of the binding strips are bent over so as to lie in grooves in the surface of the lid and are secured therein by means of loops of wire passing through the lid and around said strips, the ends of said loops being subsequently twisted together and soldered over and to the binding strip. If desired the binding strips may be soldered together at their points of intersection or contact in order to increase the strength and safety of the arrangement.

Further, and in order to render the case the more secure strips may be disposed in grooves transversely of the ends of the packing case, such additional strips being secured to the bottom and end of the case by fasteners such as nails, or bifurcated rivets, the heads of which lie inside said case and the outer ends of which are treated as above set forth. The ends of each of such additional strips should be long enough to be bent over and lie in grooves in the bottom and lid of the case so as to extend across and be sealed to the adjacent strips which pass around the sides of the case.

The invention will be described with ref-

erence to the accompanying drawings of which Figure 1 is a perspective view of a packing case and Figure 2 is an enlarged fragmentary section on the line 2-2 of Figure 1. In Figure 1 the binding strips at one end are shown with wire loop fasteners whilst those at the other end are shown with nail or rivet fasteners, and some of the nails for retaining the binding strips are shown unsealed. The sides *a*, *a*, and end *b*, *b* are secured together and to the contiguous edges of the bottom *c* by means of nails *d* or the like in the usual manner and a pair of parallel grooves *e*, *e* is cut in the outer faces of the sides *a*, *a*, and the bottom *c*, said grooves *e*, *e*, running continuously along three faces of the case. A pair of transverse grooves *f*, *f*, is cut in each of the outer faces of the ends *b*, *b* and said grooves *f*, *f* are continued to meet the grooves *e*, *e* in the bottom *c*, and the sides *a*, *a*.

In each of the grooves *e*, *e* and *f*, *f* is disposed a strip of hoop iron *g*, *g*, *g*¹, *g*¹, secured to the case by means of nails *h* bifurcated rivets *i* or wire loops *j* passing through the sides *a*, *a* and ends *b*, *b* or bottom *c* with the heads or central portions as the case may be on the inside of the case and having their outer ends bent over and sealed to the corresponding strip *g* by means of solder as at *k*.

At each end *b* one of the strips *g*¹ has its ends each passed under and bent around the adjacent strip *g* on the corresponding side *a* and the bottom end of the other strip *g*¹ is similarly secured to the bottom portion of the strip *g*.

When the case has been packed for transit the top *m* is put on and secured if desired to the contiguous edges of the sides *a*, *a* and ends *b*, *b* by means of nails *n* or the like and grooves *o*, *o* and *p*, *p* are formed on the outer face of the top *m* to correspond respectively with the grooves *e*, *e* and *f*, *f*, the grooves *p*, *p* extending only to meet the adjacent groove *o*.

The free ends of the strips *g*, *g*, *g*¹, *g*¹ in the grooves *e*, *e* and *f*, *f* are bent over so as to lie in the corresponding grooves *o*, *o* and *p*, *p* and to overlap one another and said strips *g*, *g* and *g*¹, *g*¹ are then secured to the top *m* by means of wire loops *s* passing through the top *m* and being bent around said strips. The free ends of each wire loop *s* are then twisted together and sealed to the corresponding strips *g* or *g*¹.

as at *t*. The overlapping ends of the strips *g* and *g*¹ are apertured and secured to the top *m* by a bolt *q* and nut *r* and are also soldered over as at *u*.

5 At the point where the ends of the strips *g*, *g* and *g*¹, *g*¹ meet the groove may be enlarged and a quantity of solder or the like sufficient to receive the impression of a seal may be deposited on the joint as at *u*.

10 If desired, the edges of the case may be surface-bound in the usual manner with strips or hoop iron or the like secured by means of the nails *d* and *n*, the ends of each strip being soldered together, and short 15 pieces of hoop iron or the like may be secured and sealed by their respective ends to adjacent strips *g* and the edge surface binding strips in the manner previously described.

15 I claim:—

1. Closing means for a packing case, consisting of hoop iron or like binding strips secured to and around said case in grooves in the body of the case by means of fasteners disposed at intervals along the lengths 25 of said binding strips, the fasteners passing through the case from the inside outward and having their outer ends sealed to said strips by soldering or the like.

2. Closing means for a packing case as

claimed in claim 1, wherein the binding strips are secured to the bottom and sides of the case by fasteners the heads of which lie inside said case and the outer ends of which are bent over the binding strip and sealed thereto with solder, and to the lid of the case by wire loops passed through said lid, the free ends of each of said loops being subsequently twisted together and soldered over and to the binding strip.

35

3. Closing means for a packing case as claimed in claim 2 wherein additional strips are disposed in grooves transversely of the ends of the packing case, said additional strips being secured to the case, substantially as set forth.

40

4. Closing means for a packing case as claimed in claim 1, wherein the binding strips are soldered or otherwise sealed together at their points of intersection.

50

5. Closing means for a packing case as claimed in claim 2, wherein the binding strips are soldered or otherwise sealed together at their points of intersection.

45

6. Closing means for a packing case as claimed in claim 3, wherein the binding strips are soldered or otherwise sealed together at their points of intersection.
